BOOMERANG

Arnold H. Marler, 8 Wendell Ave., Weston,
Ontario, Canada

Filed May 19, 1964, Ser. No. 80,064

Term of patent 14 years

(Cl. D34—15)

FIGURE 1 is a perspective view of a boomerang showing my design;

FIGURE 2 is a top plan view thereof;

FIGURE 3 is a bottom plan view;

FIGURE 4 is an enlarged sectional view taken substantially on the plane indicated by line 4—4 in FIGURE 2;

FIGURE 5 is an enlarged sectional view taken substantially on the plane indicated by line 5—5 in FIGURE 2; and

FIGURE 6 is a fragmentary sectional view taken substantially on the plane indicated by line 6—6 in FIGURE 2.

The characteristic feature of my design resides in the combination on a boomerang of enlarged edge portions

extending from the lower edge on one end and the upper edge on the opposite end that fade into the plane of the body at the center, and having parallel grooves extending throughout the surface of one side, all as shown.

I claim:

The ornamental design for a boomerang, substantially as shown and described.
